FILING CABINET

Cornelius H. Van Donk, Green Bay, Wis.

Application April 8, 1942, Serial No. 438,069

1 Claim. (Cl. 312—192)

My invention refers to filing cabinets having stationary drawers or trays, and more particularly to filing cabinets wherein a hinged top cover and a hinged front panel are included to facilitate access to file contents stacked within the tray or drawer.

The object of my invention is to provide some means associated with the front panel and cover, wherein said cover may be swung to open position to free the front panel for independent manual swing. Thus, when the cover is open, the operator can readily inspect the file contents and separate the same at the desired point for extraction of a document. The front panel is swung in the same manner as a book. Hence, the proper index tab is found, and the contents is opened at the proper place by outward swing of the panel. It will be noted that under normal conditions, the front panel remains in a vertical position holding the file material in a corresponding position for inspection of the index.

As far as I am aware, cabinet files of this general type are constructed in such a manner that when the cover is raised, the front panel is automatically tilted forward, and the file contents will also drop forward and rest upon the front panel in such a position that the file contents or index is obstructed at the angle of vision. The material or contents will necessarily have to be swung back in order to visualize the index, whereby the contents can be readily inspected.

I am also familiar with a cabinet wherein the tray or drawer is horizontally slideable in and out, the cabinet having a swinging front panel under control of mechanism associated with the top swinging cover, whereby the tray is under control of the cover movement, permitting manual swing of the front panel when the cover is open, and arranged with certain spring control, whereby the front panel is closed incidental to closure of the top cover.

It will be noted that this mechanism primarily embodies a movable or slideable drawer, which is expensive in manufacture, and the lever and spring mechanism for controlling the movements is also complicated and expensive, bearing in mind that springs in their use for closing the front panel, due to crystallization, lose their resiliency and are frequently broken. Furthermore, the springs associated with the front panel, when weakened, fail to give the desired compression of the file contents when the drawer is closed.

While the front panel in the above structure may be manually swung when the drawer is distended, it should be borne in mind that even though the front panel is capable of manual move-

ment back and forth, the structure is impractical from a manufacturing standpoint.

My cabinet having a fixed or stationary drawer is mechanically equipped to avoid the disadvantages just mentioned by permitting the front panel to remain in a vertical position, and the same can be manually swung as the user may desire, independent of the top cover. Hence, the front panel is capable of swinging back and forth independent of the top cover to permit more clearance of the file contents when the file is open for use, due to the fact that the front panel does not necessarily remain inclined outwardly when the file is in use. The front panel may be swung closed to its vertical position after the document sought has been removed.

Due to the fact that this type of file is frequently positioned at the side of the operator's chair and the front panel is in open position, should the operator desire to leave the chair, it would be necessary to push the file out of the way. Under such conditions, the front of a file of my construction would be manually closed, and the same condition would occur in the event that the file were flush with the front of the desk.

It is also apparent that the manual backward and forward movement of said front panel will permit the material therein to be readily nested in its vertical position after each operation to facilitate ready reference to documents.

Briefly, for accomplishing the desired function, I employ broadly any mechanical means associated with the front swinging panel and the top swinging cover, whereby the front panel is independently moved back and forth when the top cover is open. When the top cover is closed, movement of the same will positively close the front panel.

Hence, the mechanism for accomplishing this feature may embody any kind of link motion directly connecting the swinging elements, or some mechanism indirectly connecting the same.

With the above and other objects in view, my invention consists in certain peculiarities of construction and combination of parts, as will be hereinafter fully set forth with reference to the accompanying drawing and subsequently claimed.

In the drawing:

Figure 1 is a diagrammatic sectional elevation of a filing cabinet embodying the features of my invention.

Figure 2 is a similar view showing a modified form of actuating mechanism indirectly connected to the swinging cover.

Referring by characters to Figure 1 of the

drawing, A indicates the cabinet having a bottom B and a front panel C and a swinging top cover D. The top cover is connected to the rear cabinet wall by a hinge 1 having a barrel extension 2, which is slidably mounted upon a rod 3 carried by the top cover. The front panel C is provided with a hinge pivot 4 at its lower end and is preferably formed with wings 5. However, any suitable slide hinge extension mounted upon a track may be substituted for the barrel extension mentioned.

As shown in this exemplification of my invention, the side walls of the cabinet have pivoted thereon bell crank levers 5', the arms of which are connected by links 6 to barrel extensions 2 of the hinge members 1. The other arm of each bell crank lever is connected by a pin 7 to a link 8, the pin being slidable in a slot 9 formed at the associated end of the link. The other end of each link 8 is pivotally connected to the front panel C through the wing 5.

In order to permit free swinging movement of the front panel when the top cover is closed, the pin 7 of the bell crank lever will ride forward in said slot 9 when the top cover is swung open and slid downwardly, as indicated in dotted lines, it being understood that this swinging and sliding movement is permitted through the rod-and-hinge connection, but these elements form no part of my invention.

When the top cover is swung downwardly in its closed position, however, the pin 7 of the bell crank lever 5' will engage the rear end of the slot 9 and, thus, positively close the front panel, as indicated in full lines in Figure 1.

In order to provide a limited adjustment of the closing movement of the panel C, I provide a set screw 7', which is adapted to engage the pin 7, whereby the desired adjustment is had to thus insure squeezing or compression of the file contents when the cover is closed. It is to be understood, however, that any mechanical means for such adjustment may be employed.

With particular reference to Figure 2, it should be noted when the cover D is swung open, owing to the fact that the closing mechanism of the panel is free from said cover, this panel may be manually swung to a position as indicated in dotted lines. The stack of records contained in the cabinet box, which may be tightly packed, are then loosened so that the operator may open the same at any point and swing the forward volume in an angular position. The indexes at this division line may then be read and any records removed that may be required. The operator can then conveniently restack the records by oscillating the panel backwardly to close up the stack gap, or further records may be added to said stack.

Hence, when the lid is closed should the stack be of increased volume from back to front, the panel may not close fully due to the engagement of the cover against the end of the lever C'. In this event the adjusting screw 7' would be manipulated to permit full closure of the cover and said adjustment would also permit squeezing of the volume of records from back to front, whereby the cover and panel would be closed with refer-

ence to each other. It will also be noted when the cover is fully closed it engages the panel actuating lever and locks said panel in its closed position.

Figure 2 of the drawing illustrates a modified form of my invention wherein the actuating bell crank lever 6' is directly engaged by the cover D when the latter is closed, and said engagement is effected through the adjusting bolt 7''. The link 8' in this exemplification of the mechanism is connected to one arm of the bell crank and the wing 5 of the front panel.

In this instance, the cover D is directly connected to the cabinet by a hinge 1'. Hence, said cover is only capable of swinging movement upon its hinge, as indicated in dotted lines. It will be noted that the top cover D, in this case, is not connected by links to the swinging front panel, and it only serves as an engaging means for the bell crank lever 6', whereby the front panel is positively closed incidental to closure of the top cover. Hence, the front panel may be freely swung back and forth when the cover is open; it being understood that said front panel, in all instances, is frictionally held in its manual swinging movement, it being understood that the panel is limited in its extreme outward movement by stops, indicated at X, or any other suitable means.

It should be understood that any lever front cover actuating means, in practice, may be suitably encased to present smooth inside walls for the filing tray. It should be noted that the upper arm of the bell crank lever may be varied as to angle by manipulating the adjustable pin 7'', whereby the pressure upon the front panel C is increased or decreased when the top cover D is swung downwardly to engage the upper edge of the panel C. This feature is important, bearing in mind when the cabinet cell is loaded and the parts may become loose, they are thus capable of exerting pressure so as to insure proper closing.

While I have shown several forms of mechanism for accomplishing the desired results, it is understood that I may vary such forms within the knowledge of the skilled mechanic and within the scope of the claim.

I claim:

A filing cabinet comprising a body having a top cover hinged to the body adjacent to its rear end and a front swinging panel hinged at its lower end to said body, means operatively connecting said cover and panel together including a bell crank pivoted at its angle to said body adjacent to the hinge of the cover and having a forwardly projecting upper arm and a downwardly extending lower arm, a link pivotally connecting the lower arm to the panel adjacent to its pivot, the outer end of said upper arm being free and arranged in the path of the swinging movement of the cover, and an adjustable pin extending from the end of the upper arm of the bell crank to vary the angle of said upper arm with relation to the cover, whereby said cover, when swung to its closed position, will exert a variable pressure upon the panel incidental to its inward movement for completing its closure with reference to the aforesaid closure movement of the cover.
